UNITED STATES PATENT OFFICE.

SAM H. LIBBY, OF EAST ORANGE, NEW JERSEY, ASSIGNOR TO SPRAGUE ELECTRIC COMPANY,
A CORPORATION OF NEW JERSEY.

ELECTRIC CARRIER SYSTEM.

No. 910,931.

Specification of Letters Patent.

Patented Jan. 26, 1909.

Application filed August 1, 1906. Serial No. 328,718.

To all whom it may concern:

Be it known that I, SAM H. LIBBY, a citizen of the United States, residing at East Orange, county of Essex, State of New Jersey, have invented certain new and useful Improvements in Electric Carrier Systems, of which the following is a specification.

The present invention relates to electrically-propelled carriers for operation on overhead run-ways as a telpher, and has for its object to provide a simple and reliable system whereby a load may be raised or lowered at a given station, and then transferred to another station without requiring the attendance of the operator between stations, there to be lowered or raised, and the carrier again returned to the first or sending station.

The present invention in its various aspects will be more fully understood and its objects and advantages will more clearly appear from the following description thereof taken in connection with the accompanying drawing which shows diagrammatically an electrical equipment of a carrier and a preferred form of distribution system between a sending and four unloading stations.

Reference being had to the drawing, L and L' indicate current-supplying mains, and 1, 2, 3, 4 and 5 are trolley wires or conductors connecting the several stations together. The conductors 1 to 4, inclusive, are continuous throughout their length, while the conductor 5 is made up of a section 6 at the sending station, a main section 7 between the sending station and the first receiving station, and sections 8, 9, 10 and 11 arranged at the receiving stations. The various sections of conductor 5 are insulated from each other. Conductor 3 and section 7 of conductor 5 are electrically connected to line L. Conductor 4 is connected to line L'. Conductor 1 is normally dead, but may be connected to line L by means of a normally open push-button 12 at the sending station, or similar push-buttons 13, 14, 15 and 16 at the receiving stations. Conductor 2 is also normally dead but may be connected to line L through either of the normally open push-buttons or switches 17, 18, 19, 20 and 20^a located respectively at the several stations. Similarly, sections 6, 8, 9, 10 and 11 are normally dead but may be connected to line L through the respective

push-buttons 21, 22, 23, 24 and 25. Sections 8, 9, and 10 may also be connected to line L by means of the switches 26, 27 and 28, adapted to be operated in any suitable manner, as for example, by means of ropes, said ropes hanging down within reach of an operator on the floor or ground. At the sending station there is arranged a fixed stop 29 and there is a similar stop 30 at station 11. At the stations adjacent the sections 8, 9, and 10 are stops 31, 32 and 33, respectively, which may conveniently be associated with the switches 26, 27 and 28 so as to be capable of operation in unison therewith.

The carrier equipment is illustrated as comprising a traverse motor M and a hoisting motor M'; R being a reversing switch for the traverse motor, and R' a reversing switch for the hoist motor. Since the two motors are illustrated as series motors the reversing switches are of usual types arranged to change the relative connections between the field and armature windings of their respective motors in order to reverse the direction of rotation of the motors; the switch R being illustrated as of the cylinder type and the switch R' of the electromagnetic type comprising interlocked solenoid switches. The carrier is provided with five current-collecting devices 34, 35, 36, 37 and 38 adapted to run upon the trolley wires 1, 2, 3, 4 and 5, respectively.

Assuming the carrier to be at rest at the sending station, the bucket or hook controlled by the hoisting motor may be raised and lowered by pressing the buttons 12 and 17, respectively. When the button 12 is pressed, current flows from line L through this button, to trolley wire 1, through the current-collector 34, through the actuating coil 39 of one member of the reversing switch R', through the interlock 40 of the other member of the reversing switch R', to current-collector 37 and trolley wire 4, and thence to line L'. Thus the solenoid 39 is energized and its core 41 is raised. Current may now be traced from line L, through trolley wire 3, current-collector 36, contacts 42 and 43 of the reversing switch, armature of motor M', contacts 44 and 45 of the reversing switch, field winding of motor M', to current-collector 37, trolley wire 4, and thence to line L'. The motor M' now operates in the

proper direction to raise the load, and continues to do so until the push-button is released and the solenoid 39 deenergized. To lower the load, push-button 17 is closed, and current then flows from line L, through this push-button to trolley wire, through current-collector 35, to the second solenoid 46 of the reversing switch R', through interlock 47 associated with the core of solenoid 39 to current-collector 37, trolley wire 4, and thence to line L'. The solenoid 46, being thus energized, lifts the core 48 and a circuit may be traced through the hoisting motor from line L, trolley wire 3, current-collector 36, contacts 49 and 50 of the reversing switch, armature of the hoisting motor, contacts 51 and 52 of the reversing switch, field of the hoisting motor, and thence through current-collector 37 and trolley wire 4, back to line L'. The load is now lowered and the lowering operation continues as long as the push-button 17 is held closed.

When it is desired to start the carrier toward one of the receiving stations, the button 21 at the sending station is depressed, and current then flows from line L to push button 21, trolley section 6, current-collector 38, through the reversing switch R and motor M to current-collector 37, trolley wire 4, back to line L'. The motor M now begins to rotate in the direction to move the carrier away from the sending station. As soon as current-collector 38 emerges from section 6 upon section 7, the push-button 21 may be released and the carrier will continue in operation by reason of the section 7 being connected directly to line L independently of the push-buttons.

If it is desired to cause the carrier to stop at the first receiving station, namely, that station adjacent section 8, the switch 26 and stop 31 are brought into the position shown, whereby section 8 is deenergized and when the carrier enters thereon causes the current to the traverse motor to be interrupted and this motor to stop. Shortly before the carrier comes to rest an arm r upon the reversing switch R strikes against the stop 31, and as the carrier proceeds, the reversing switch is thrown in the opposite position from that shown, namely, to such position that when current is again supplied to the traverse motor the carrier is moved back toward the sending station. By means of push-buttons 18 and 13 the load may be lowered and raised and by the push-button 22 the section 8 may be energized and the carrier started back toward the loading station. When the sending station is reached, the current-collector 38 enters once more upon the dead section 6, depring the traverse motor of current, and the arm r of the reversing switch engages with stop 29 to effect the operation of the reversing switch to the position shown, namely to that position wherein the motor is ready

when supplied with current to cause the carrier to proceed again toward the receiving stations.

If it is desired to cause the carrier to move beyond section 8, as, for example, to section 10, then the switch 26 is closed and the switch 28 is opened, the switch 27 being in the position shown in the diagram. Sections 8 and 9 are now connected directly to line L and section 10 is deenergized. Under this condition the carrier continues to run until the current collector 8 enters upon the section 10 and the traverse motor M is no longer supplied with current. Just before the carrier stops, the stop 33 engages the arm r and the reversing switch R is thrown to its opposite position. The load may be lowered and raised by manipulating the push-buttons 20 and 15 and the carrier may be started back towards the loading station by closing the push-button 24 exactly as explained above in connection with the first receiving station. By closing switches 26, 27 and 28 the carrier may be made to traverse the entire distance to the final station where the circuit is interrupted on section 11 and the reversing switch operated by means of stop 30. Energization of the hoisting and transfer motors may be controlled at the last receiving station by means of the push-buttons 16, 20^a and 25 in the same manner as at the other stations.

It will be seen that the system is adapted for operation in connection with any desired number of stations; the switches at the several stations being identical in grouping so that their corresponding switches at the several stations may be connected in multiple if desired, thereby reducing the number of conductors necessary. No switches corresponding to the switches 26, 27 and 28 are shown at the sending station and at the extreme receiving station for the reason that it is unnecessary to have the sections 6 and 11 energized except through the push-buttons, and it is furthermore preferable to have fixed stops at these latter stations in order that the carrier may not over-run.

Although I have described in detail only the best form of my invention now known to me the invention is not limited to the particular arrangement shown, but its scope is indicated in the appended claims.

What I claim as new and desire to secure by Letters Patent of the United States, is:

1. In a carrier system, a plurality of stations, a trolley conductor having an isolated section at each of said stations, a carrier adapted to travel between said stations, a propelling motor on said carrier arranged to receive current from said trolley conductor, a switch at each station for connecting the adjacent isolated section to the source of supply, a reversing switch for said propelling motor carried by said carrier, and a stop located at each station and moving with said

- first named switch for throwing said reversing switch when said first named switch is open.
2. In a carrier system, a plurality of stations, a trolley conductor having an isolated section at each of said stations, a motor-driven carrier adapted to travel between stations and to receive current from said trolley conductor, a switch at each station for connecting the adjacent section to the source of supply, means at each station for reversing the carrier motor when the corresponding switch is open, and a second switch at each station for energizing the adjacent section independently of the first switch.
3. In a carrier system, a plurality of stations, trolley conductors including a conductor having an isolated section at each station, a carrier adapted to travel between said stations, a propelling motor and a hoisting motor on said carrier, current collectors on said carrier for connecting said motors to said trolley conductors, means at each station independent of said trolley conductors for reversing the propelling motor, means for energizing said isolated sections at will, and switches at each station for energizing certain of the said conductors to cause the hoisting motor to operate in either direction at will.
4. In a carrier system, a plurality of stations, trolley conductors including a conductor having an isolated section at each station extending between said stations, a carrier adapted to travel between said stations, a propelling motor and a hoisting
- motor on said carrier, a reversing switch on said carrier for said propelling motor, means at certain of said stations for deenergizing the adjacent conductor sections and for operating the reversing switch for the propelling motor when the carrier enters upon said sections, and additional means at said latter stations for energizing and deenergizing said sections at will.
5. In a carrier system, a plurality of stations, trolley conductors including a conductor having an isolated section at each station extending between said stations, a carrier adapted to travel between said stations, a propelling motor and a hoisting motor on said carrier, reversing switches on said carrier for said motors, means at certain of said stations for deenergizing the adjacent conductor sections and for operating the reversing switch for the propelling motor when the carrier enters upon said sections, means at said latter stations for energizing and deenergizing said sections at will, electromagnetic actuating-means for the hoisting-motor reversing-switch, trolley conductors for controlling said actuating means, and means at each station for energizing or deenergizing said latter conductors at will.

In witness whereof, I have hereunto set my hand this 24 day of July, 1906.
